INJECTION AND PRODUCTION TOOL FOR OIL AND GAS WELLS

John Lynes, Albuquerque, N. Mex., assignor to Oil Recovery Corporation, Albuquerque, N. Mex., a corporation of New Mexico

Application January 8, 1953, Serial No. 330,334

4 Claims. (Cl. 255—1.4)

This invention relates to a production tool for oil or gas wells, which tool may also be employed for the treatment of wells, as by injection of chemicals. The tool is characterized by means capable of drilling into and sealing off formations in the side walls of the borehole, the borehole having been previously drilled by conventional means.

The increasingly great distances to which oil and gas wells are being drilled has presented the industry with acute problems relating to efficient means for completing or bringing in a well. Even after the difficult step of identifying a productive stratum has been accomplished, many wells are lost due to inadequate means for isolating the stratum from contamination, particularly from water strata in the well, and for causing it to deliver its contents of oil or gas to the surface.

Cementing is a conventional and much used method for completing a well, whereby a string of pipe is set adjacent a selected formation, and cement is pumped into the annular space between the pipe and borehole. Next, by means of a gun perforator, the attempt is made to render the formation productive by shooting through the pipe and cement layer. One of the drawbacks of this operation is that the cement, having been pumped in at tremendous pressures, may infiltrate and seal off productive zones despite the perforations subsequently made.

Another way of producing a well involves the use of packer tools which are set in a well bore to seal off a selected formation whereupon treating or swabbing operations, or both, are performed through the supporting pipe. Packer tools are subject to breakage and dislocation in the well, and are less permanent than a cementing job, and both means have the disadvantage that they operate on the formation from within the confines of the drill hole.

The present invention, by contrast, is designed, when located adjacent a selected formation, to penetrate it laterally for considerable distances, and thereupon to seal off the lateral bores thus produced in such manner as to isolate them from the drilling mud and other contaminating fluid like water, in the drill hole proper. At the same time, automatic means are provided for opening a fluid line connection between the lateral bores and the surface. With the tool constituting the invention thus situated, areas of the selected formation are made accessible to a far greater extent, for treatment and production, than are made accessible by conventional means such as those first described.

Other and further advantages of the invention will be described in connection with the drawing, wherein:

Fig. 1 is an elevation, partly in section, of the tool comprising the invention, in condition for lowering into a drill hole;

Fig. 2 is a similar view showing the tool after having been located for treating or production operations in the drill hole of a well;

Fig. 3 is a section taken on lines 3—3 of Fig. 1; and Fig. 4 is a section taken on lines 4—4 of Fig. 1.

In the drawing, the main body member or tool housing is designated at 10, adapted for connection with the upper pipe member 11 by a threaded upper coupling 12. Upper pipe member 11 is intended for support from and rotation by conventional lengths of drill string (drill pipe or tubing, not shown). The base of housing 10 terminates in a lower threaded coupling 13 for the attachment of one or more selected lengths of pipe, such

2

as lower pipe 14. At the base of lower pipe 14 is attached a toothed shoe 15 (Fig. 2) for engaging the base of the drill hole, whereby the housing 10 will be secured against rotation.

By these means, it will be apparent, the tool may be set in a well at a predetermined position, by measuring the distance from the well bottom upwards to the desired location, and providing a lower pipe 14 in one or more sections having the desired total length for support.

Within the body 10 is the cylindrical gear head 16, mounted for vertical non-rotational movement by means of keys 17 slidable in the slots 18 formed on the inner walls of body 10. The head 16 has a lower hollow recess 25 and a detachable base member 19, these members providing the bearings for the hollow rotating shafts 20 and 21, which are driven by means of pinions 22 and 23. The upper portions of shafts 20 and 21 are pierced by ports, whose purpose will be explained below.

A hollow drive coupling 26 is carried internally of the head 16 and is connected to the upper pipe 11 by means of collar 27. On the lower end of coupling 26 is formed a hollow driving gear 28 which connects with pinions 22 and 23.

Disposed for limited vertical movement within the hollow coupling 26 and member 19, is stopper 30 the upper portion of which is hollow and carries an upper removable ring 31. Ports 33 are formed in the walls of the hollow portion of stopper 30. The base of stopper 30 is solid and carries a lower flange 32 to prevent removal of stopper 30 from member 19. A number of sealing rings designated at 34, 35 and 36, are located in the spaces between the stopper 30, coupling 26, head 16, and the base member 19 to provide fluid tight joints.

Stopper 30, in the down position shown in Fig. 1, is designed to close off the entry of fluid such as drilling mud from the main body member 10 into upper pipe 11, the ports 33 of stopper 30 being closed by member 19. Additional means are necessary, under circumstances explained below, to maintain stopper 30 in the Fig. 1, or down, position. These may comprise a shear-pin 60 positioned in hole 61 bisecting the solid part of the stopper directly beneath member 19 and designed to be sheared off by member 19 when stopper 30 is forcibly moved upwards.

Pivoted to the lower ends of hollow shafts 20 and 21 are the lateral drill and feeder pipes 40 and 41, by means of the hollow capped Cardan-type universal joints 42 and 43 which provide a flexible fluid line connection between hollow shafts 20—21 and pipes 40—41. Drill pipes 40 and 41 are provided at their lower ends with the drilling bits 44 and 45, and with a series of ports 46. Above the ports 46 on pipes 40—41 are the cone-shaped formation seals 47—48, formed of resilient material such as rubber. These are secured against upward movement along the pipes 40—41 by means of the metal rings 51—52.

The base of the main body member is pierced by a pair of large ports 53—54 internally of which is formed the deflector 50 in the shape of a cone having concave sides, and provided with a flat crown 55.

The operation of the tool will now be described. In the Fig. 1 position the tool is in condition for lowering into the drill hole, it being assumed that the formation to be treated or produced has been located by other means, and that the length of lower pipe 14 has been adjusted to bring the tool to the proper position when the shoe 15 reaches and engages the well bottom. In the Fig. 1 position it will be seen that housing 10 is coupled to upper pipe 11, retaining the gear head in its upper position and the drill pipes 40—41 in their retracted position.

In the Fig. 1 position, furthermore, while fluid from the well may enter the ports 53—54 into the body 10 and from thence into the recess 25 of the driving head 16 through the ports 46 and 24, it is blocked from further upward passage by the presence of the stopper 30, which is held in closed position by shear-pin 60, and whose ports 33 are sealed off in the Fig. 1 down position by the base member 19.

Location of the tool at the desired level in the well, as has been explained, will lock the main housing against

rotation by the action of the toothed shoe 15 in engagement with the well bottom. In this condition, clockwise rotation of the supporting drill pipe will cause the threaded coupling 12 to disconnect, as shown in Fig. 2. At the same time continued rotation of the drill pipe, and its inherent weight (supplemented if necessary by downward pressure) will cause the gear head to move downwardly in the keyway 17-18 while the drive coupling 26 is being rotated. Rotation of the coupling 26 causes rotation of shafts 20-21, the feeder pipes 40-41 and drill bits 44-45, through the gears 28 and pinions 22-23.

Continuance of this downward rotary movement applied to pipe 11 will cause the bits 44-45 and drill-feeder pipes 40-41 to be deflected by member 50, to exit through the ports 53-54 and to penetrate the side walls of the drill hole, forming lateral side wall bores designated at 60 and 61.

When side wall bores have been thus formed to a predetermined depth, the resilient seals 47 and 48 will be carried by pipes 40-41 into contact with the mouths of the side wall bores, as indicated at 62 and 63, Fig. 2. Due to the fact of their diameter and conical construction, and also due to the rotary action imparted to their supporting feeder pipes, the seals 47-48 will be longitudinally compressed against the rings 51-52, with a consequent wadding action such as illustrated in Fig. 2. In this condition the seals have been forced to expand laterally within the mouths of the respective side wall bores, thus providing a very effective sealing-off means isolating the side wall bores from the main drill hole and its contents.

After the sealing-off operation just described, continued downward movement of the gear head 16 will finally cause contact between the base of stopper 30 and the crown 55 of deflector 50; shearing off the pin 60 and causing the stopper 30 to be lifted into its upper position shown in Fig. 2. In this position the ports 33 of stopper 30 are opened into the recess 25, thus completing an uninterrupted fluid line connection between the side wall bores 60-61 and pipe 11 leading to the surface, which connection is via the ports 46, pipes 40-41, hollow joints 42-43, hollow shafts 20-21, ports 24, recess 25, ports 33, into the hollow stopper 30, and thence to pipe 11. It should be noted that the means described above permit the tool to be placed in operative position in fluid connection with a formation while avoiding the presence of a column of liquid in the pipe 11 or the supporting drill string above. This situation is provided by the arrangement of stopper 30 and particularly its associated shear-pin 60 which is designed to prevent the liquid pressure in the drill hole from prematurely opening the stopper 11 when it is desired to maintain the upper pipe string in dry condition. The advantage of this arrangement resides in that the formation, when penetrated and sealed off, is immediately relieved of the pressure of the column of drill mud in the main drill hole, and natural pressures in the formation have only to combat a column of air in the upper pipe string. Accordingly, even very weak natural pressures in the formation will cause a flow of its contents into the tool, and the necessity of swabbing out the upper pipe is eliminated.

On the other hand, if it is desired first to treat the formations by the injection of treating fluids such as acids, the pipe 11 and the upper string may be filled with such fluids at any convenient time prior to final location of the tool in the selected formation. On the opening of stopper 30 pumping operations may promptly commence.

Should it be desired to remove the tool from its operative position in the well, in order to exploit a different formation or a different well, rotation of the supporting pipe and slowly raising the supporting pipe, will cause the seals 47-48 to break connection with the side wall bores and the feeder pipes to retract into the body member 10, whereupon the assemblage may be withdrawn.

From the foregoing, it will be understood that there has been described a versatile tool which, accomplishes new results in penetrating and sealing off of considerable lateral areas of a producing stratum, in a single operation. Of great importance are the means described whereby all operations can be automatically controlled from the surface merely by simple vertical and rotational movement of the supporting pipe. Of similar importance are the sealing means provided, without which the side

wall bores would be contaminated by the drill hole fluids and could not be exploited separately.

While no dimensions are generally necessary for understanding the operation of the tool, the practical length for the drill and feeder pipes, measured between the drill bits and seals respectively, will be governed by the type of formation encountered, the nature of which would be established in the drilling of the main well bore. Any tight formation highly resistant to drilling will limit the length of the drill and feeder pipe to about one hundred and fifty feet, since the torque developed would tend to collapse a pipe of greater length. On the other hand, in a porous formation the pipe length could be several hundred feet, permitting a penetration of this distance into the formation. It will be seen that in either case the tool offers unique possibilities in penetrating and exploring large lateral areas of formations adjacent the main bore-hole.

By making the housing 10 in a plurality of coupled sections, and the drill-feeder pipes in a plurality of jointed sections the tool can be easily modified to provide various side wall penetrations within the above footages. Also, the feeder pipes should be formed of resilient steel so that by altering the concavity of the deflector member, the feeder pipes if desired, may be deflected into the side wall formations at angles substantially horizontal; the drawing in this respect being by way of illustration only.

What is claimed is:

1. A tool of the type described comprising a hollow main body member dimensioned for lowering into the main drill hole of an oil or gas well by a drill string connection from said body to the surface, means for supporting said body member against rotational movement when positioned for operation in the drill hole, at least one side wall penetrating drill and feeder pipe in inoperative position retained in said body member, said drill and feeder pipe being capped by a drilling bit, driving means in said body member operable by movement of said drill string connection to force said drill and feeder pipe laterally from said body member into a formation to form a lateral bore therein, sealing means carried by said feeder pipe mounted for engagement with the mouth of said lateral bore, a fluid passageway formed between ports in said feeder pipe and a channel leading through said body to said drill string connection, and stopper means contained in said fluid passageway opening the passageway upon completion of said side wall bore automatically actuated by said driving means.

2. A tool of the type described comprising a hollow main body member dimensioned for lowering into the main drill hole of an oil or gas well by a drill string connection from said body to the surface, means for supporting said body member against rotational movement when positioned for operation in the drill hole, at least one side wall penetrating drill and feeder pipe in inoperative position retained in said body member, said feeder pipe being capped by a drilling bit, driving means in said body member operable by movement of said surface pipe connection to drive said feeder pipe laterally from said body member into a formation to form a lateral bore therein, said driving means comprising a gear head mounted for vertical movement within said body member and supporting a geared drive shaft coupled to said drill and feeder pipe, a drive coupling containing in said gear head and connected to said drill string for rotational movement and carrying a driving gear connected to said geared drive shaft, a lateral exit port in said body for said drill and feeder pipe, sealing means carried by said feeder pipe mounted for engagement with said lateral bore, a fluid passageway formed between ports in said drill and feeder pipe and a channel leading through said gear head into said drill string, and stopper means in said passageway opening the passageway upon completion of said side wall bore, said stopper being actuated by a trip brought into contact with said stopper by downward movement of said gear head.

3. A tool of the type described, comprising a hollow main body member, means for suspending said body member in the main hole of an oil or gas well from a drill string, means for anchoring said body member against rotary movement adjacent a selected well formation, at least one sidewall penetrating drill and feeder pipe carrying a rotary drilling bit in inoperative position contained in said body member, means including an

exit port in said body member for guiding said drill and feeder pipe laterally into the sidewall of said well, driving means operable by rotation and lowering of said drill string for rotating said pipe while advancing said pipe through said exit port, a channel formed between ports in said pipe and said body member, compressible sealing means carried on said pipe between said ports and said body member for engaging said sidewall, a shutoff in said channel normally in closed position when said pipe is in inoperative position, and means for opening said shutoff automatically actuated by said driving means at a selected interval determined by the desired extent of penetration of said pipe into said sidewall.

4. A tool of the type described, comprising a hollow main body member, means for suspending said body member in the main hole of an oil or gas well from a drill string, means for anchoring said body member against rotary movement adjacent a selected well formation, at least one sidewall penetrating drill and feeder pipe carrying a rotary drilling bit in inoperative position contained in said body member, means including an exit port in said body member for guiding said drill and feeder pipe laterally into the sidewall of said well,

driving means operable by rotation and lowering of said drill string for rotating said pipe while advancing said pipe through said exit port, a channel formed between ports in said pipe and said body member, compressible sealing means carried on said pipe between said ports and said body member for engaging said sidewall, a shutoff in said channel normally in closed position when said pipe is in inoperative position, and means for opening said shutoff automatically actuated by said driving means at a selected interval in the movement of said pipe into said sidewall measured by the arrival of said sealing means into engagement with said sidewall.
